UNITED STATES PATENT OFFICE.

WALTER E. BOSTWICK, OF ALGONAC, MICHIGAN.

JAR-CLOSURE.

No. 847,640.

Specification of Letters Patent.

Patented March 19, 1907.

Application filed December 26, 1905. Serial No. 293,180.

To all whom it may concern:

Be it known that I, WALTER E. BOSTWICK, a citizen of the United States, residing at Algonac, county of St. Clair, State of Michigan, have invented a certain new and useful Improvement in Jar-Closures; and I declare the following to be a full, clear, and exact description of the same, such as will enable others skilled in the art to which it pertains to make and use the same, reference being had to the accompanying drawings, which form a part of this specification.

This invention relates to closures for jars. It has for its object an improved sealing closure for preserving-jars.

In the drawings, Figure 1 is a perspective of a jar and cover. Fig. 2 is a section, showing the cap and the manner in which it engages on the neck of the jar. Fig. 3 is a perspective of the top of the jar. Fig. 4 is a perspective of a disk which covers the hole in the top of the jar. Fig. 5 is a perspective of a disk which covers the disk of Fig. 4. Fig. 6 is a section of an air-extractor used in sealing the jar.

The body of the jar is of any approved design, having a neck 1, around the top of which is a projection 2 of smaller diameter, leaving a shoulder 3. When the projection emerges from the main part 1 of the neck, the neck is adapted to hold a gasket 4.

The cap is provided with a flaring flange 6, that engages tightly on the gasket 4. The cap also has a central hole 7, and on the upper or external side of the cap, concentric with the hole 7, is a recess 8 of a size to receive a sealing-disk 9. A recess 10, of larger diameter, is concentric with the hole 7 and forms a receptacle for a securing-disk 11.

The sealing-disk 9 is of any flexible material impervious to air, preferably a small disk of quite flexible rubber. The securing-disk 11 is of any suitable material, preferably a piece of paper covered with cement. The recesses 8 and 10 have coaxial cylindrical walls and flat bottoms. The bottom of the recess 8 is smooth to serve as a valve-seat, and the bottom of the recess 10 forms an annular surface surrounding the recess 8 and serving also as a valve-seat.

The residuum of air left in the jar after it

has been nearly filled with the material to be preserved is drawn therefrom by means of a tubular nipple 12, made of sufficiently durable material to withstand the slight air-pressure which will be developed and provided at its base end with a cavity 13, in which the disk 9 has free movement and ample room to yield, and allow the air within the jar to escape through the hole 7 and out from under the disk. The edge of the nipple 12 engages the annular surface surrounding the recess 8 and should engage so closely therewith as to make a substantially airtight joint. The several parts thus assembled, namely—the jar-top, the nipple, and the disk 9—constitute an air-pump, in which the disk 9 is the valve.

In use the jar filled nearly full of material to be preserved and having the gasket 4 in place has the cap 14 placed thereon and pressed down tightly. The sealing-disk 9 is then placed loosely over the hole 7, and nipple 12 is then seated on the annular surface surrounding the recess 8, with the cavity 13 so located with respect to the hole 7 and the cavity 8 that the sealing-disk 9 may yield upward readily into the cavity 13, and the air is drawn out from the jar through the nipple to as great an extent as is practically possible. This may be done by means of an air-pump connection, which is not shown, or it may be done by applying the mouth to the nipple and withdrawing the air by suction. Upon opening the nipple or allowing the air to flow into it again the sealing-disk 9 is pressed down tightly on its seat and prevents the air from entering the jar, and the jar is now sealed and may remain in this condition indefinitely; but inasmuch as the sealing-disk 9 is flexible and light it may be easily drawn away from its seat or may be accidentally displaced therefrom, and to prevent this a protecting-disk 11 is placed over it and preferably secured to its seat by a cement, which may be a simple paste or mucilage. Thus prepared the jar with its contents may be handled with considerable roughness and will stand transportation and all ordinary handling without becoming unsealed.

What I claim is—
An implement for use in extracting air

from vessels, having in combination a tube provided with an unimpeded passage therethrough and a seating-rim, and a flexible disk adapted to coact with said tube as a valve and thereafter to remain as a closure to the aperture through which the air is withdrawn, substantially as described.

In testimony whereof I sign this specification in the presence of two witnesses.

WALTER E. BOSTWICK.
